UNITED STATES PATENT OFFICE.

MICHAEL ALBERT DREES, OF PESHTIGO, WISCONSIN, ASSIGNOR OF ONE-HALF TO NELLIE P. HUNT, OF PESHTIGO, WISCONSIN.

WRITING-TABLET.

No. 907,477.

Specification of Letters Patent.

Patented Dec. 22, 1908.

Application filed March 23, 1908. Serial No. 422,678.

To all whom it may concern:

Be it known that I, MICHAEL ALBERT DREES, a citizen of the United States, and a resident of Peshtigo, in the county of Marinette and State of Wisconsin, have invented a new and Improved Writing-Tablet, of which the following is a full, clear, and exact description.

My invention relates to letter sheets and tablets therefor, my more particular object being to provide a device in which one or any larger number of sheets of paper may be kept temporarily together, and arranged in connection with suitable parts for facilitating the folding and pasting of the letter sheets.

Reference is to be had to the accompanying drawings forming a part of this specification, in which similar characters of reference indicate corresponding parts in all the views.

Figure 1 is a plan view of the tablet made up of letter sheets and provided with a swinging member which I call a folder, and which is used as a form upon which the letter sheets are folded, the folder in this instance being shown as swung away from the letter sheets; this view also showing an address slot with which each sheet is provided for reading, as an address, the superscription at the top of the letter; Fig. 2 is a view similar to Fig. 1, but showing the folder resting upon the uppermost letter sheet in order to facilitate the folding of the letter; Fig. 3 is a view somewhat similar to Fig. 2, but showing an additional step, to wit: the bottom edge of the letter sheet turned over the folder toward the top, with its slot opposite, the superscription at the top of the letter; Fig. 4 shows the device having the sheet a step further advanced, in that after being folded as shown in Fig. 3, the sides of the sheet are bent inward under the folder; Fig. 5 shows the letter sheet thus folded as detached from the tablet; Fig. 6 shows another step in the construction, the letter sheet as folded in Fig. 5 being again doubled upon itself, the flap, however, being still free; Fig. 7 shows the completion of the construction shown in Fig. 6, the gummed flap being pasted down upon the body portion, so as to fold the folded letter sheet and give the entire structure the appearance of an envelop containing an inclosure; Fig. 8 is a longitudinal section upon the line 8—8 of Fig. 1, showing the general arrangement of the tablet when ready for use; Fig. 9 is a section upon the

line 9—9 of Fig. 2, showing the folder as resting upon the tablet in order to serve as a form upon which to fold the letter; Fig. 10 is a sectional view upon the line 10—10 of Fig. 3, showing the appearance of the tablet when the sheet has been partially folded; Fig. 11 is a section upon the line 11—11 of Fig. 4, showing the letter sheet with its right and left sides bent toward each other around the folder; Fig. 12 is a section upon the line 12—12 of Fig. 5, showing the appearance of the letter sheet when it reaches the step of folding shown in Fig. 5; and Fig. 13 is a vertical section through the completed structure shown in Fig. 7, and discloses how the gummed flap when sealed holds all other parts of the sheet in position.

Mounted upon a board 14 of paper, straw or the like, are a number of letter sheets 16, each provided with an address slot 15, the sheets being secured together in the form of a tablet, their edges 16^a opposite the ear 14^a being glued or otherwise caused to adhere together in any known manner. At 17 is a smaller board, preferably thinner than the board 14, and connected with it by a flexible strip 18, which may be of thin leather or tough paper, said board 17 serving as a folder. The strip 18 serves as a hinge for connecting the folder 17 and the board 14 together, in order to allow the folder 17 to be shifted into the positions indicated in Figs. 1 and 2. Each letter sheet is provided with a flap 16^b integral with it, this flap being substantially of the same general outline as the ear 14^a of the board 14.

The construction may best be understood by reference to the several successive figures, showing respectively the different steps in the folding of the letter sheets. Beginning with Fig. 1, it will be noted that the folder 17 can be thrown backward from the letter sheets, so that the folder rests flat upon any surface supporting the tablet. We will now suppose that one or more sheets 16 have been written. As the principle for operating a plurality of sheets is the same as for a single sheet, I will describe merely the steps relating to a single sheet. The operator having finished writing a sheet, which is, of course, the top sheet, swings the folder 17 over onto this sheet, as will be understood from Fig. 2. He next bends the bottom edge of the letter sheet toward the top and over the folder as shown at 16^b, see Figs. 3 and 10, so as to ex-

pose, through the slot, the address at the top. He next bends the sides of the sheet inward and under the folder, as shown at 16^a (see Figs. 4 and 11). He now detaches the letter sheet from the tablet, working the sheet slightly, if need be, in order to disengage it from the folder, and simply pulling it off from the latter. The letter sheet now has the appearance indicated in Fig. 5. The operator next bends the bottom of the member 16^a upward, so as to apparently reduce the size of the letter sheet to one-half the size shown in Fig. 5. This gives it the appearance shown at 16^b in Fig. 6. The gummed flap 16^b is next moistened and secured upon the folded letter sheet 16^a, and the construction is finished.

It matters not whether the folder 17 be employed as the guide for measuring the edges of the letter sheet as bent upon said folder. If desired, the measurement may be done in any other way or indicated by any agency independent of the folder. For convenience, however, it will be found that the folder itself offers the readiest means of measurement. While I preferably begin the folding, as indicated in Fig. 3, I do not limit myself to this particular order of procedure, as obviously the letter sheet may first be bent up from the bottom and the sides folded over afterwards.

I do not limit myself to the exact proportions of the various parts shown, for the reason that these may be varied within reasonable limits without departing from the spirit of my invention.

Having thus described my invention, I claim as new and desire to secure by Letters Patent:

40 1. A writing tablet, comprising a plurality of sheets, each having a flap at one end, and a board of less length and width than the sheets and flexibly connected to the tablet at

the end opposite the flaps of the sheets, said board being adapted to be swung over upon 45 the uppermost sheet and the latter folded upon the board.

2. A device of the character described, comprising a writing tablet having letter sheets, each provided with an integral flap, 50 and a board flexibly connected to the tablet and adapted to rest upon the same, said board being of less width and length than the sheets and upon which a sheet is adapted to be folded. 55

3. A device of the character described, comprising a board, letter sheets mounted thereupon, each having an integral flap at one end and a slot adjacent to the end having the flap, a folder loosely connected with said board and adapted to swing relatively thereto, said folder being flat and smaller than said board and upon which the letter sheets are adapted to be bent into a shape corresponding to that of the folder. 60 65

4. A device of the character described, comprising a board provided upon one of its edges with an ear, a number of letter sheets mounted upon said board and provided with gummed flaps registering with said ear, a 70 folder smaller than said board, and a flexible connection from said folder to said board.

5. The combination of a writing tablet containing a plurality of letter sheets detachably mounted thereupon, a folder of 75 smaller width and length than said writing tablet and movable relatively thereto, and a flexible connection from said folder to said writing tablet.

In testimony whereof I have signed my 80 name to this specification in the presence of two subscribing witnesses.

MICHAEL ALBERT DREES.
